TURRET CONSTRUCTION

Harry B. Maris, Riverdale, Md.

Application July 10, 1941, Serial No. 401,754

9 Claims. (Cl. 114—8)

(Granted under the act of March 3, 1883, as
amended April 30, 1928; 370 O. G. 757)

This invention relates to improvements in turret construction and more particularly to such improvements involving the rollers and roller paths which enable the turret structure to be rotated relative to the foundation which supports it.

It has heretofore been the practice in turret construction to support the weight of the turret upon a series of wide solid rollers having flanged ends. Roller paths ground as accurately as possible to plane surfaces were formed on the portion of the turret which rested on the rollers and on the portion of the foundation upon which the rollers rested. The portions of the structure upon which these roller paths were ground fitted snugly down upon the roller faces between the roller flanges. Lateral movement of the turret with respect to its foundation resulting from the recoil of the turret guns or the explosions of enemy projectiles in proximity to the turret was resisted by the roller flanges. In order to prevent vertical movement of the turret relative to its foundation due to the recoil action or the explosion of projectiles, holding down clips were formed on the turret structure. These were in the shape of brackets which projected from the turret and extended beneath an overhanging portion of the foundation structure normally clearing it by a small amount.

The use of large flanged solid rollers presented several disadvantages. It necessitated the employment of large and heavy foundations in the turret structures upon which roller paths could be ground. The use of holding down clips required a large clearance space between the barbette and the portion of the turret structure which revolved inside it. The large size of the rollers employed introduced a large factor of torque into the recoil action since the diameter of the rollers introduced a large vertical displacement between the roller paths. Furthermore, the machining of wide roller paths such as required by this structure is a task very difficult of accomplishment. On the other hand the presence of any irregularities in the turret paths caused the entire weight of the turret structure to be supported by only a small number of rollers with the result that rollers must be of such size that the entire weight of the turret could be borne by a very few of them. Moreover, roller path irregularities other than those due to faulty machining are commonly encountered. These are due to changes in the metal caused by uneven temperature conditions and also by the hogging and sagging of the ship due to wave motion. These lat-

ter irregularities may be many times greater than those normally encountered as the result of faulty machining.

The training gear normally employed with these installations included a large spur gear meshing with the training rack formed on the turret foundation. These gears regardless of their large size must be protected from recoil stresses and could not be used normal to the direction of gunfire. The driving mechanism was therefore placed as near the plane of fire as possible so that the recoil would tend to separate the gear from the rack.

Another disadvantage attending the use of large flanged rollers was the inability to prevent the entry of dirt and foreign matter between the bearing surfaces since it was impossible to adequately house the roller assembly. It was necessary to protect the spur training gear from the whip due to the firing of the single wing gun and from shock resulting from the impact of an enemy projectile, by a release in the driving motor.

Turret installations aboard ship are subject to long periods of non-use with the turret maintained at a fixed angle of train. During these periods the motion of the ship subjects the rollers and the roller paths to constant wear due to the small vibratory vertical movements of the turret relative to its foundation. This wear is called fretting abrasion.

It is an object of this invention to provide a turret construction which will result in a great saving of weight over those previously used. It is a further object of this invention to provide a turret construction which will considerably reduce the necessary clearance between the rotating parts of the turret and the barbette. It is a still further object of this invention to provide a turret construction utilizing hollow flexible rollers capable of yielding to afford distribution of the turret weight when irregularities are encountered in the roller path clearances. It is also an object of this invention to provide a turret construction utilizing a series of horizontally disposed hollow rollers and a series of vertically disposed hollow rollers for the purpose of absorbing horizontal forces without the development of torque. It is another object of this invention to provide a turret construction utilizing flexible rollers which will yield upon the application of severe stress to allow solid contact between the rotating and the fixed portions of the turret structure for transmission of said forces from the rotating to the fixed structure. It is another object of this invention to provide a roller and

roller path assembly which will allow the rollers to be completely enclosed and thus effectively guard the assembly against the intrusion of dirt and foreign matter and allow it to be effectively lubricated. It is another object of this invention to provide a training system which will be much more rugged than the type using the spur gear and will be capable of absorbing the shock of recoil whip or of projectile impact without the necessity of a release mechanism. It is another object of this invention to provide a means for protecting the rollers from fretting abrasion. Other objects will become apparent from a consideration of the following description taken together with the accompanying drawings in which:

Fig. 1 is a plan view of the pan floor of a turret showing the top of the roller and roller path assembly and having a portion cut away to show a portion of the training rack;

Fig. 2 is a plan view of a fragment of a turret wall showing the worm gear arrangement for training the turret;

Fig. 3 is an elevational view of one of the worm gears used to drive the turret together with the details of its bearing system;

Fig. 4 is an elevational view in section of a fragment of the turret taken along the line 4—4 of Fig. 3;

Fig. 5 is a side elevational view in section of a portion of the turret wall and turret foundation wall showing the arrangement of the roller path, rollers and holding down means;

Fig. 6 is a side elevational view of a section of the turret and foundation walls extending around the turret from the sectional view of Fig. 5;

Fig. 7 is a plan view in section of a portion of the structure shown in Fig. 6 taken along line 7—7 of that figure, and

Fig. 8 is an elevational view in section of a modified form of roller path and roller assembly.

The details of one embodiment of the invention may best be seen in Fig. 5 where there is shown a turret wall 1 positioned in coaxial relationship to, and outside of, a cylindrical turret foundation 2 with the lower end of the turret wall extending downwardly past the upper end of the turret foundation and having a slight clearance with respect thereto. Welded to the inner side of the turret wall 1 is an upper path ring 3 having formed on its lower face a surface 4 ground as accurately as possible to a true plane. The upper end face 5 of the turret foundation 2 is likewise ground to a plane surface parallel to 4. Between these surfaces is positioned a series of hollow steel rollers 6. Welded to the inner face of the upper path ring 3 is a cylindrical side wall 7 extending downwardly from the ring 3 and spaced from the foundation 2 by only a small clearance. Machined in the upper end of the inner face of foundation 2 is an annular recess having a vertical wall 8 ground as accurately as possible to a true cylindrical surface. Opposite to this recess is formed a cooperating annular recess having a vertical wall 9 ground to a true cylindrical surface. Taken together these two recesses form a single annular recess of rectangular cross-section. Positioned in this recess is a series of rollers 10 which are similar in construction to the rollers 6. Also ground in the opposing faces of the foundation 2 and the side wall 7 is a key way in which floats a key 11. Welded to the inner surface of the foundation wall 2 is a ring 12 of rectangular cross-section having its upper sur-

face accurately ground to a plane. The lower end of the side wall 7 is ground to a conical surface 13 sloping upwardly and out. Welded to the inside of the side wall 7 with its upper surface 5 level with the bottom of the rollers 10 is the pan plate 14. As best shown by Fig. 6 there are provided in the wall 7 a pair of removable sections 15 of which only one is shown in Fig. 6. These are bolted to the ring 3 by means of lag bolts 16 and by their removal the rollers 6 and 10 may be inserted in their respective places. There is likewise provided in wall 7 a pair of removable sections 17 of which only one is shown in Fig. 6. These sections are normally held in place by upwardly directed lag bolts 18 which attach the sections to the wall 7. These removable sections are spaced 180° apart.

Between the lower end face 13 of the wall 7 and the upper face of ring 12 are positioned a series of locking blocks 19 as shown in Fig. 6. These blocks are for the purpose of removing the weight of the turret from the horizontal rollers 6 when the turret is not in use. The number and lengths of these blocks are such that their combined length would be somewhat less than half the circumference of the wall 7. As shown in Fig. 6 a series of slots 20, each slightly longer than one of the blocks 19 and spaced apart by the same distance, are cut in the conical surface 13 of the wall 7 for the admission of the blocks 19. Where these slots are cut the lower end of wall 7 extends horizontally rather than at an angle with the horizontal as shown in Fig. 5. At the left hand end of each of these slots as shown in Fig. 6 a downwardly extending lug 21 having a radially directed right hand face is welded to the surface 13. Located opposite the lug 21 is a lug 22 of similar configuration welded to the upper surface 23 of ring 12. Also welded 30 to the surface 23 at the right hand end of the slot 20 as shown in Fig. 6 is a lug 24 having a vertical side 25 which slopes as shown in Fig. 7. The right hand end of block 19 has the same slope, as shown in Fig. 7. The blocks 19 have 35 a cross-sectional shape similar to that of the space between the surface 13 and 23, as shown in Fig. 5.

The operation of the blocks 19 to lock the turret from movement while it is not in use is as follows:

The blocks are assembled in the portions of the space between surfaces 13 and 23 provided with the slots 20, with the turret turned in a clockwise direction from the position of rest it 55 normally occupies when not in use. The extent of this movement is such that each of the lugs 21 will have traveled in a clockwise direction the length of one of the slots 20. The relationship between the wall 7 and the ring 12 will 60 now be that shown in Fig. 6. With the blocks 19 in place the turret is now trained in a counter-clockwise direction until it occupies its normal position of rest. When in this position the lugs 21 will have moved in a counter-clockwise direction an amount such that each block 19 will no longer lie within a slot 20 but will have been positioned entirely beneath one of the unslotted sections of 13. When in this position the blocks 19 prevent any vertical movement of wall 7 with 65 respect to foundation. In order to release the blocks 19 from their locking position the turret is now trained in a clockwise direction until the wall 7 and the ring 12 again occupy the positions shown in Fig. 6. Now any further movement 70 of the turret in a clockwise direction will cause 75

the surfaces 25 of the lugs 24 to eject the blocks 19 from their places and they will fall clear of the turret structure. Means such as chains may be provided to loosely attach the blocks to the foundation wall 2.

The method of assembly of the roller path structure described above may be as follows:

The surface 5 should first be ground to a plane over the entire circle and the surface 8 should then be ground to an accurate circular shape. The slot for key 11 and the upper surface 23 of ring 12 could then be ground or machined to the desired degree of accuracy. A collar of steel plate of a height convenient for the machinist could then be placed on the upper face 23 of ring 12. The faces on the inner side of turret wall 1, the lower surface 4 of ring 3 and the outer surface of wall 7 would then be ground. The grinding completed, the turret would now be lifted on jacks, the collar resting on ring 12 removed and the turret would be lowered on to its support on rollers 6 which would be rolled into place between ring 3 and foundation wall 2 through the removable sections 15. When all the rollers were in place and carrying the weight of the turret the rollers 10 could be rolled into their seat by rotation of the turret while they are being inserted through the removable section 15. The key 11 is in sections of such a length that they may be inserted by removal of sections 17. A sample section of the key should be machined to a free sliding clearance around the entire circle of its groove. With this segment as a pattern the other segments should be machined to the same dimensions and then inserted through the opening left by removal of section 17.

Figs. 1, 2, 3 and 4 show the improvements in the training mechanism contemplated by the invention. The training rack 30 is shrunk on the outside of a downwardly extending annular member 31 welded to the bottom of the pan plate 14. While immovable with respect to member 31 under ordinary stresses, the rack 30 will slip under the application of unusually heavy stresses before the other components of the training gear will be harmed. Meshing with the rack 30 are a pair of worms 32 driven through pinions 33 secured on the worm shafts. Motor 34, through a shaft 35 and spiral gears 36 and 37, drives shaft 38 on the ends of which are secured gears 39 meshing with pinions 33. As shown in Fig. 2 the single motor 34 drives a pair of worms 32. A similar installation will be placed on the opposite side of the structure. An installation of this type may be provided with worms each having sufficient strength to take a shock load of 500,000 pounds, which will be sufficient to absorb all shocks resulting from firing or the explosion of an enemy projectile against the outside of the turret, without the necessity of provision of a release means. In ship installations the motors could be placed along the fore and aft center line of the ship. Such positioning of spur gears is impossible due to the necessity of keeping the spur gear out of a position normal to the line of fire. Nor can a spur gear installation be so positioned that the driving mechanism is carried by the turret stool, since, if so carried, the spur gear could not be separated from the rack upon recoil, for all angles of fire.

Fig. 8 shows a modification of the roller path assembly such as illustrated in Fig. 5. In the event that longer and larger rollers than the roller 6 shown in Fig. 5 are required, the modification shown in Fig. 8 is preferred. In this modifica-

tion the dimensions of the roller 6 have been increased and the roller has been divided into three sections. This is made necessary by the necessity of tapering a roller of this length for frictionless rolling on a circular track. With the long roller, provision of the required taper is not practicable. Straight rollers may be used in short lengths.

With the roller so divided each section rotates at a slightly different rate and the different sections would need to be kept in line by a tapered guide which is not shown. The numbers and functions of most of the parts in this figure are the same as those in Fig. 5. However, in order to increase the width of the lower roller path the plate 40 has been welded to the upper portion of the inside of the inside of foundation 2. The pan plate 14 is welded directly to the inner surface of this plate and the rollers 10 rest on top of the pan plate, the slot for their accommodation being formed entirely in wall 7. The wall 7 has thus been split into 2 rings the lowermost of which is seen below the pan plate 14, being welded to plate 40. The blocks 19 are employed as before. In this case, however, the training rack has been mounted on the turret stool. The rack is indicated at 41. Its upper surface is bevelled in the shape of a cone extending upwardly and out. It is supported on a ring 43 welded to the turret foundation above which is a plate 44 welded to ring 43. In assembling the training rack the base support 43 is first welded in place with sufficient clearance to allow the different sections of the training rack to be seated against plate 40, the bottom face of which is bevelled to match the upper surface of rack 41. The key plate 44 is then forced into place under high pressure, securely locking the training rack in position. After 44 is seated, it is welded to 43, thus insuring a permanent lock for the training rack, which however can be made to rotate under the application of heavy stresses.

The hollow rollers shown in the various embodiments should have a wall thickness approximately $\frac{1}{6}$ the diameter of the roller. With such a thickness the roller will be as strong as a solid roller of the same length and diameter. However, solid rollers of the same length and diameter could not be used since the inherent inaccuracies in the roller paths plus those induced by irregular temperature distribution and movement of the ship in a seaway would produce irregularities in roller path clearance which would result in injury either to the rollers or the roller path or both. However, by the use of flexible rollers which yield under stress the distribution of the load of the turret and of the forces of recoil is such as to reduce the stress on any one part of the structure and thus to avoid injury to it.

Utilization of the invention should save weight in the order of 100 tons per turret with the embodiment shown in Fig. 5. In spite of this decrease in weight the assembly would be stronger because of its compactness and flexibility. Upon the application to the rollers of stresses of the magnitude of those due to recoil, they will yield sufficiently to allow solid contact between the wall 7, roller 10 and the bottom of the roller slot in the turret foundation 2. This will also allow solid contact between the sides of the key slot in wall 7 and foundation 2, and the key 11. Thus heavy stress cannot injure the roller path or the rollers, since these stresses will be communicated directly from the moving to the stationary parts of the turret and thence

to the structure of the ship or other mounting platform. Horizontally acting stresses will be resisted by the contact of turret wall 1 with turret foundation 2 and also at the opposite side of the turret by the contact of wall 7 with the turret foundation 2.

The structure according to the invention presents a smooth exterior rotating surface having no projections which might be fouled by battle damage. This is a distinct advantage over the construction previously used. Because of the considerable decrease in interference between the rotating turret and the barbette due to the elimination of holding down clips, the diameter of the barbette could be materially reduced while maintaining sufficient clearance. This would allow the saving of a strip of barbette armor of considerable length. If advantage is taken of this feature a total saving in weight in large 3-gun turrets could be as high as 200 tons per turret.

The use of small rollers and simple cross sections for the roller paths offers a possibility of the use of material of higher quality and the employment of better heat treatment. The shape of the various paths and parts of the assembly is such that rolled welded strips can be advantageously employed, with the greater uniformity and greater tensile strength which is available in such shapes over that obtainable with previously used forms of construction. The entire assembly can be packed in grease, thus giving better protection from dirt and moisture and better lubrication than can be obtained with an open bearing structure such as that necessary when flanged rollers are employed. The most important advantage resulting from the invention is the elimination of torque from horizontal thrusts communicated from the pan plate to the turret foundation.

It should be understood that the practice of the invention is not limited to the embodiments illustrated and described but only by the scope and limitations of the appended claims.

The invention described herein may be manufactured and/or used by or for the Government of the United States of America for governmental purposes without the payment of any royalties thereon or therefor.

I claim:

1. A gun turret having a cylindrical turret wall and fixed cylindrical foundation wall coaxial therewith and extending upwardly inside the lower end thereof, said foundation wall having a plane, horizontally extending, upwardly facing surface formed on its upper end, a ring-shaped member secured to the inside of said turret wall and lying above said surface, said member having a similar but downwardly facing surface formed thereon, a series of horizontally extending flexible hollow rollers positioned between said surfaces, a cylindrical wall extending downwardly from said member inside, coaxial with said foundation wall and having a small clearance with respect thereto, said foundation wall and said cylindrical wall having annular recesses formed therein which cooperate to form a raceway of rectangular cross-section having vertical side walls accurately formed to cylindrical shape, a series of vertically disposed hollow flexible rollers positioned in said raceway and under normal conditions maintaining a clearance between said cylindrical wall and said foundation wall, said cylindrical wall and said foundation wall having a key

way formed therebetween, a key in said key way and a pan plate secured to said cylindrical wall with its upper surface lying in substantially the same plane as the lower ends of said vertically disposed rollers.

2. A gun turret having a cylindrical turret wall and fixed cylindrical foundation wall coaxial therewith and extending upwardly inside the lower end thereof, said foundation wall having a plane, horizontally extending, upwardly facing surface formed on its upper end, a ring-shaped member secured to the inside of said turret wall and lying above said surface, said member having a similar but downwardly facing surface formed thereon, a series of horizontally extending flexible hollow rollers positioned between said surfaces, a cylindrical wall extending downwardly from said member inside, coaxial with said foundation wall and having a small clearance with respect thereto, said foundation wall and said cylindrical wall having annular recesses formed therein which cooperate to form a raceway of rectangular cross-section having vertical side walls accurately formed to cylindrical shape, a series of vertically disposed hollow flexible rollers positioned in said raceway and under normal conditions maintaining a clearance between said cylindrical wall and said foundation wall, said cylindrical wall and said foundation wall having a key way formed therebetween, and a key in said key way.

3. A gun turret having a cylindrical turret wall and fixed cylindrical foundation wall coaxial therewith and extending upwardly inside the lower end thereof, said foundation wall having a plane, horizontally extending, upwardly facing surface formed on its upper end, a ring shaped member secured to the inside of said turret wall and lying above said surface, said member having a similar but downwardly facing surface formed thereon, a series of horizontally extending flexible hollow rollers positioned between said surfaces, a cylindrical wall extending downwardly from said member inside, coaxial with said foundation wall and having a small clearance with respect thereto, said foundation wall and said cylindrical wall having annular recesses formed therein which cooperate to form a raceway of rectangular cross-section having vertical side walls accurately formed to cylindrical shape, a series of vertically disposed hollow flexible rollers positioned in said raceway and under normal conditions maintaining a clearance between said cylindrical wall and said foundation wall.

4. A gun turret having a rotating portion and a foundation portion, said rotating portion including a cylindrical side wall and a circular pan plate fixed to the inside of said cylindrical side wall to rigidly maintain the cylindrical contour of said side wall, said foundation portion being unsupported radially in the plane of the pan plate, a series of horizontally disposed rollers positioned between superimposed horizontally extending surfaces of said portions and normally bearing the weight of said rotating portion, a series of vertically disposed rollers positioned between opposing vertically extending cylindrical surfaces formed on said portions with their bases in a plane substantially aligning with the upper surface of said pan plate and establishing and normally maintaining a fixed small clearance between vertically extending surfaces of said rigid side wall and said founda-

tion portion, said rollers being so compressible as to yield upon the application to said rotating portion of stresses in a direction normal to their respective roller paths, thereby temporarily removing the clearances established and normally maintained by said rollers and allowing contact between opposing surfaces of said portions which extend in directions parallel to their respective roller paths.

5. In a gun turret having a rotating portion, a foundation portion and a series of horizontally disposed rollers positioned between horizontally extending surfaces of said portions and normally bearing the weight of said rotating portion; means for locking said rotating portion against vertical or horizontal movement relative to said foundation portion while said rotating portion is not in use, said means comprising a series of blocks, said portions having opposing surfaces each formed with a series of recesses in matching locations, whereby, for a particular angle of train, a series of spaced-apart chambers are formed between said surfaces wherein said blocks may be loosely positioned, said surfaces between said chambers being spaced apart to snugly fit said blocks, the end walls of said recesses and the ends of said blocks being so formed that upon training said rotating portion in one direction from said angle of train said blocks will become tightly held between said surfaces and will hold said rotating portion against vertical or horizontal movement with respect to said foundation portion and said blocks will be injected from said recesses upon rotation of said rotating portion in the opposite direction from said angle of train.

6. In a gun turret having a rotating portion, a foundation portion and a series of horizontally disposed rollers positioned between horizontally extending surfaces of said portions and normally bearing the weight of said rotating portion; means for locking said rotating portion against vertical or horizontal movement relative to said foundation portion while said rotating portion is not in use, said means comprising a series of blocks, said portions having opposing surfaces so shaped that, for a particular angle of train, a series of spaced-apart recesses are formed wherein said blocks may be loosely positioned, and a plurality of lugs formed upon said opposing surfaces, said lugs being so shaped and so positioned as to force said blocks into tightly fitting relationship between said surfaces upon movement of said rotating portion in one direction from said angle of train and to eject said blocks from said recesses upon rotation of said rotating portion in the opposite direction from said angle of train.

7. In a gun turret having a rotating portion, a fixed foundation, and a series of horizontally disposed rollers positioned between horizontally extending surfaces of said rotating portion and said foundation, and normally bearing the weight of said rotating portion; means for locking said rotating portion against vertical movement relative to said foundation while said rotating portion is not in use, said means comprising a series of blocks, a shelf formed on said foundation upon which said blocks may be positioned, said rotating portion having downwardly facing surfaces formed thereon and lying above said shelf, said surfaces being formed to provide a first series of recesses between it and said shelf, each of which will loosely accommodate one of said blocks, said surface being fur-

ther formed to provide a second series of spaced recesses alternating those of said first series and each of such size that one of said blocks may be tightly held therein whereby vertical or horizontal movement of said rotating portion relative to said foundation will be prevented, a first series of depending lugs having radially extending lateral faces formed on said surfaces and each positioned adjacent one end of one of said first series of recesses, each of said lugs occupying a similar position with respect to its recess, a second series of similarly shaped upwardly directed lugs formed on the upper surface of said shelf and so located that each may lie directly under one of said dependent lugs and a third series of upwardly directed lugs, the lugs of said third series being formed on said shelf and each being positioned at the opposite end of one of said first series of recesses from said previously mentioned lugs, each of said third series having an inclined vertical face, whereby when the lugs of said first series lie directly above those of said second series and said blocks are positioned in said first series of recesses, movement of said rotating portion in one direction will cause said first series of lugs to move said blocks into said second series of recesses, whereas under the same conditions movement of said rotating portion in the opposite direction will cause the lugs of said third series to eject said blocks from their positions between said shelf and said downwardly facing surface formed on said rotating portion.

8. A gun turret having a rotating portion and a foundation portion, said rotating portion comprising a cylindrical side wall and said foundation portion comprising a cylindrical wall surrounding a portion of said rotating side wall and being radially unsupported in the region where such overlap occurs, a horizontally extending annular roller path formed on each of said portions and lying above and outside the facing surfaces of said rotating side wall and said wall, a series of compressible rollers positioned between said roller paths and normally bearing the weight of said rotating portion, a cylindrical roller path formed on each of said facing surfaces, a series of compressible rollers positioned between said cylindrical roller paths, said portions being formed with horizontally extending superimposed surfaces, said surfaces and portions of said facing surfaces being normally held from contact by a very small clearance by said rollers, the compressibility of said rollers being such that upon the action of any abnormal thrust such as those encountered upon recoil of the guns carried by said turret said rollers will yield sufficiently to allow said surfaces to come into contact and thus communicate the stresses directly from said rotating portion to said foundation portion through direct contact of said portions, said cylindrical wall yielding in its radially unsupported region to allow such direct contact over a large area thereof.

9. In a device of the class described, a fixed cylindrical base member, a movable cylindrical member, means for supporting the movable member against shock and for concentric rotation relative to the fixed member, one of said members being disposed at least partially within the other, an annular ring having a prestressed fit over the outside of the inner member and disposed in the vicinity of the supporting means, said annular ring being of small

cross-sectional area relative to its circumference and of resilient material, power drive means for rotating the annular ring relative to the fixed member including means automatically locking the annular ring in any position relative to the fixed member, whereby any shock imparted to said movable member tending to

either start or stop rotational or translational movement thereof will be cushioned by circumferential stretching and local slippage of the annular ring relative to the inner cylindrical member thus making the annular ring an integral part of the shock supporting system.

HARRY B. MARIS.
